[57] ABSTRACT

The base-catalyzed self-condensation of isovaleraldehyde yields a mixture of threo- and erythro-2-isopropyl-5-methyl-3-hydroxyhexanal. The reaction conditions can be so chosen as to favor predominance of one isomer over the other. Upon vacuum distillation of the mixture, one of the isomers preferentially dehydrates yielding 2-isopropyl-5-methyl-2-hexenal as a distillate and unchanged 3-hydroxy-2-isopropyl-5-methylhexanal as the residue. These aldehydes are the parent members of a class of compounds composed of 2-isopropyl-5-methylhexanal, 3-hydroxy-2-isopropyl-5-methylhexanal, 2-isopropyl-5-methyl-2-hexenal, and the alcohol and carboxylic acid derivatives of these aldehydes, the ester and ether derivatives of the alcohols and acids, as well as certain other alcohol and ketone derivatives. These compounds are useful as tobacco additives to modify the taste of the tobacco, and/or as intermediates for the preparation of tobacco additives.

8 Claims, No Drawings

2-ISOPROPYL-5-METHYL-2-HEXENAL, 2-ISOPROPYL-5-METHYLHEXANAL, 3-HYDROXY-2-ISOPROPYL-5-METHYLHEXANAL, AND DERIVATIVES THEREOF AS TOBACCO FLAVORANTS

DISCLOSURE OF THE INVENTION

This application is a continuation-in-part of each of Ser. No. 806,682 filed Mar. 12, 1969, Ser. No. 57,414 filed June 19, 1970, and Ser. No. 73,194 filed Sept. 17, 1970, all now abandoned.

This invention relates to novel aldehydes, alcohols, acids, ethers and esters as tobacco flavorants. More particularly, this invention is concerned with 3-hydroxy-2-isopropyl-5-methylhexanal, 2-isopropyl-5-methyl-2-hexenal and 2-isopropyl-5-methylhexanal, the corresponding primary alcohols and their ethers and esters, the corresponding carboxylic acid derivatives and esters of the acids, 3-isopropyl-6-methylheptan-2-ol, 3-isopropyl-6-methylheptan-2-one and their corresponding unsaturated derivatives as tobacco additives to modify the flavor of the tobacco smoke.

The compounds to which this invention relates may be represented by the formula:

wherein Y is hydrogen, hydroxyl, lower acyloxy, or lower alkoxy; X is hydroxymethyl, lower acyloxymethyl, lower alkoxyxymethyl, 2-hydroxyethyl, formyl, acetyl, carboxyl or lower alkoxy carbonyl and y is 0 or 1. These compounds may be further classified as follows:

3-Hydroxyhexanal derivatives:

2-hexenal derivatives:

Hexanal derivatives:

wherein X is as defined above and Z is hydrogen, acyl or alkyl. Of these compounds, all but the hexen-1-ol esters and ethers within the scope of formula IB are useful as tobacco flavorants, and the unsaturated esters and ethers are useful as intermediates for the corresponding saturated esters and ethers of formula IC. By the term "lower alkoxy" is meant an alkoxy group of from one to three carbons, i.e., methoxy, ethoxy, propoxy and isopropoxy. Methoxy is particularly preferred. By the term "lower acyloxy" is meant an acyloxy group of from two to four carbons, i.e., acetoxyl, propionoxy or butyroxy with acetoxy being preferred.

It will be apparent from a consideration of the structural formulas that for compounds represented by formula IB certain geometrical isomers are possible, and for those represented by formula IA certain diastereoisomers are possible. These isomers are in-

cluded within the scope of this invention since they all impart desirable flavor properties.

These products are readily obtained by a series of reactions beginning with isovaleraldehyde which, in the first step of the synthesis, is self-condensed in the presence of a base to yield a mixture of the threo- and erythro-isomers of 3-hydroxy-2-isopropyl-5-methylhexanal. The condensation is conducted in an aqueous reaction medium having dissolved therein a strong base, such as an alkali metal hydroxide, e.g., potassium hydroxide. The reaction is usually effected at room temperature or below, i.e., temperatures at or below about 25°C. In a preferred technique, a solution of isovaleraldehyde in an organic solvent is admixed with aqueous base at reduced temperatures, preferably 0° to 5°C., and then the reaction mixture is maintained at room temperature for about 6 to about 120 hours or more, depending upon the desired product, with dehydration being favored by longer reaction times.

With a reaction time of about 6 hours 3-hydroxy-2-isopropyl-5-methylhexanal isomer A is isolated and solidifies when placed in the refrigerator, m.p. 47°-49°. Prolonged reaction time favors the production of 2-isopropyl-5-methyl-2-hexenal and 3-hydroxy-2-isopropyl-5-methylhexanal isomer B. This mixture can be separated by distillation at about 24 mm Hg, the former distilling at 95°-100°, the latter at 120°-130°.

The 3-hydroxy-2-isopropyl-5-methylhexanal and the 2-isopropyl-5-methyl-2-hexenal are readily oxidized to the corresponding acids by conventional oxidation techniques, as by bubbling air or oxygen through the aldehyde at room temperature or treatment with oxidizing agents.

The resulting acids are then esterified in known manner, as by acid-catalyzed reaction with a low molecular weight alcohol of the formula ROH, wherein R is lower alkyl. A preferred method comprises the use of perchloric acid or sulfuric acid and methanol. Alternatively, the methyl ester is obtained by reaction of the acid with diazomethane.

The 3-hydroxy-2-isopropyl-5-methylhexanal and the 2-isopropyl-5-methyl-2-hexenal are also readily reduced, as by treatment with sodium borohydride in conventional manner, to the corresponding primary alcohol, i.e., 2-isopropyl-5-methylhexane-1,3-diol and 2-isopropyl-5-methyl-2-hexen-1-ol. Alternatively, the hexenal compound can be hydrogenated under mild conditions, e.g., over a palladium catalyst, to yield 2-isopropyl-5-methylhexanal, or under more severe conditions, e.g., over platinum oxide and ferrous chloride, to yield 2-isopropyl-5-methylhexanol, which may be esterified or etherified in known manner.

The saturated hexanal may be oxidized to the corresponding acid as described above, and the acid converted to a lower alkyl ester.

All of the alcohols may be fully or, in the case of the derivatives of Formula IA, partially esterified or etherified in known manner.

As noted above, most of these products are useful as additives to tobacco, especially cigarette tobacco, to modify the flavor of the tobacco. The amount of the compound which is added to the tobacco will vary with the compound and the effect desired. In general, how-

ever, amounts of at least about 0.02 milligrams per gram of tobacco are employed. Normally amounts exceeding 0.5 mg per gram of tobacco are undesirable because of harshness. When employed in filter cigarettes higher amounts are required to achieve the same effect obtained with non-filter cigarettes.

The following examples are illustrative:

EXAMPLE I

To a cooled (0°C.) solution of isovaleraldehyde (100 g.) in 100 ml. of ether was added with stirring 200 ml. of aqueous 15 percent potassium hydroxide solution over a period of 45 minutes and at such a rate that the temperature did not rise above 5°C. After cooling at 0°C. for an additional 15 minutes, the cooling bath was removed and the mixture was stirred for 24 hours. The liquid layers were separated; the aqueous layer was washed with ether and the combined ether solutions were washed successively with 2 N acetic acid, saturated sodium bicarbonate solution, water and saturated sodium chloride solution. After drying over anhydrous magnesium sulfate, the ether was removed on a rotary evaporator and the product was distilled under vacuum on a Vigreux column. The 2-isopropyl-5-methyl-2-hexenal distilled at 95°-100°/24 mm Hg. Gas-liquid chromatography of the latter results in a peak consisting of isovaleraldehyde due to thermal retroaldol decomposition in the hot (200°C.) column inlet.

EXAMPLE II

The unsaturated aldehyde recovered in Example I was purified further by fractionation using a semi-micro spinning-band column and a manostat to regulate the pressure at 200 mm. Four fractions were collected between 135° and 136°/200 mm. Hg. The infrared (IR) and mass spectra of the combined fractions were consistent with the assigned structure; i.e., 2970 and 2880 (CH₃) 2710 (CHO), 1690 (conjugated aldehyde carbonyl), 1630 (C=C), 1470 (CH₂ + CH₃), 1423 (C-H bending), 1388 and 1370 (isopropyl), 1281 (C=C-C=O) and 1143 cm⁻¹ (isopropyl); the mass spectrum gave the molecular ion at m/e 154, and peaks corresponding to loss of 15, 43 and 57 units, in addition to those at m/e 29 and 15. The 2,4-dinitrophenylhydrazone was prepared and recrystallized from methanol, orange-red crystals, m.p. 129°-132°C., and showed one spot on thin layer chromatography using several solvent systems. Analysis.—Calc'd. for C₁₆H₂₂N₄O₄: C, 57.47; H, 6.63; N, 16.76. Found: C, 57.44; H, 6.67; N, 16.68.

EXAMPLE III

The aldol of Example I was converted to 3-hydroxy-2-isopropyl-5-methylhexanoic acid by allowing the higher-boiling fraction of Example I, 3-hydroxy-2-isopropyl-5-methylhexanal, to stand for several weeks, or by bubbling air through the viscous liquid for several days, whereupon crystals of the acid separated. Recrystallization from cold methylene chloride-carbon tetrachloride gave white needles, m.p. 88°-89°. The mass spectrum gave the molecular ion at m/e 188, with major peaks at 170, 131, 113, 102, 87, 85, 71, 69, 43, 41, 29, 27. The m/e 170 and 102 peaks arise by loss of water and by reverse aldol reaction, respectively; the others are straightforward fragmentation peaks. The IR spectrum (CH₂Cl₂) shows acid and hydroxyl OH bands at 3300-3000 and 3600-3500 cm⁻¹, and has three

carbonyl bands, for dimer (1700 cm⁻¹), intramolecularly hydrogen-bonded form (1726 cm⁻¹), and non-bonded form (1752 cm⁻¹). By the use of dioxane as a solvent the band at 1700 cm⁻¹ reverts to the bonded form (1726 cm⁻¹), thus indicating that the hydroxyl on carbon 3 is hydrogen-bonded to the carbonyl oxygen. Analysis.—Calc'd. for C₁₀H₂₀O₃: C, 63.80; H, 10.71. Found: C, 64.06; H, 10.55.

EXAMPLE IV

Methyl 3-hydroxy-2-isopropyl-5-methylhexanoate was prepared from the acid of Example III using excess ethereal diazomethane. Quantitative conversion was indicated by thin layer chromatography (Silica gel G, benzene-ethyl acetate, 9:1). The compound was chromatographed on grade III neutral alumina (100-200 mesh), using benzene as the eluent. An analytical sample was obtained by gas liquid chromatography on a 10 ft. × 1/8 in stainless steel column packed with 10 percent GE-SF-96 on Gas Chrom RZ, 100-200 mesh, flow rate = 40 ml. He/min.; column temp. 68° initial hold/4 min., program 4°/min. thereafter. The retention time under these conditions was 30 minutes. IR spectrum: 3540 cm⁻¹ (bonded OH), 1716 cm⁻¹ (bonded ester C=O). NMR spectrum: singlet, 3.66 ppm OCH₃; broad singlet, 2.35 ppm. bonded OH, overlapping doublet, 1.00 ppm (J = 6.0 cps), and 0.88 ppm (J = 5.5 cps), isopropyl methyls. The mass spectrum gave a very small molecular ion (m/e 202) peak, and peaks at m/e 184 (loss of H₂O), 171 (loss of OCH₃), 145 (base, M-C₃H₇), (OH-rearrangement), 113 (β-cleavage, loss of H₂) and 101 (loss of CH₃ from 116). Analysis. - Calc'd. for C₁₁H₂₂O₃: C, 65.31; H, 10.96. Found: C, 65.14; H, 10.95.

A 70-80 percent yield of the ester was also obtained by treatment of the acid of Example III with perchloric acid in methanol; i.e., 1 g. of acid, 25 ml. methanol and 0.1 ml. 70 percent perchloric acid was refluxed on the steam bath overnight. The methanol was evaporated and the residue taken up in ether. The ether solution was washed with dilute sodium bicarbonate solution, water and saturated sodium chloride solution, dried over anhydrous sodium sulfate and evaporated. The IR spectrum was identical to that of the ester prepared using diazomethane.

EXAMPLE V

2-Isopropyl-5-methyl-2-hexanoic acid was prepared from the unsaturated aldehyde of Example I as follows: A solution of 3.5 g. of 2-isopropyl-5-methyl-2-hexenal in 400 ml. of acetone was cooled to 10°-15°C. and stirred while bubbling nitrogen through the mixture, and 4-5 ml. of Jones' reagent was added dropwise until the orange color just persisted. The cooling bath was removed during this time. The solution was filtered; 50 ml. of water was used to wash the flask and added through the filter to the solution. The acetone was evaporated in vacuo and the mixture extracted with ether. The ether solution was extracted with 15 percent potassium hydroxide solution, and the basic extract was acidified with 10 percent sulfuric acid, followed by a final ether extraction. The ether solution was dried over anhydrous sodium sulfate and purified by preparative gas liquid chromatography on a 10 ft. × 1/8 in. copper column packed with 17 percent Carbowax 20M on Chromosorb P, 60-80 mesh, flow rate = 70 ml. He/min.; column temp. 240°. Under these conditions the clear liquid had a retention time of 18 minutes. The

IR spectrum (CCl_4) gave broad acid OH absorption at 3000-2500 cm^{-1} , and $C=C$ stretching at 1678 cm^{-1} , indicating conjugation with a carbonyl group. The mass spectrum showed the molecular ion peak at m/e 170, and large peaks at m/e 43 (base), 56 (90 percent), 69, 83, 113, 115, 128 and 155. The NMR spectrum (CCl_4) gave a 6-H doublet ($J = 6.3$ Hz) at 0.97 ppm and another 6-H doublet ($J = 7.1$ Hz) at 1.20 ppm (isopropyl methyls); a 2-H "triplet" ($J = ca. 7$ Hz) at 1.20 ppm (overlapping doublets due to methylene at C-4), a 1-H "septet" ($J = ca. 7$ Hz) at 2.90 ppm (methine of 2-isopropyl), a 1-H triplet ($J = 7.6$ Hz) at 6.76 ppm (vinylic proton at C-3), and a 1-H singlet at 11.95 ppm (acid OH).

EXAMPLE VI

Methyl 2-isopropyl-5-methyl-2-hexenate was prepared from the acid of Example V using diazomethane in a manner identical to that of Example IV. The ester was also prepared as follows: 33 g. of crude 2-isopropyl-5-methyl-2-hexenoic acid was dissolved in 300 ml. of dry methanol containing 3 ml. concentrated sulfuric acid, and the mixture refluxed for 24 hours. Solid sodium bicarbonate was used to neutralize the solution, and 200 ml water added. The methanol was evaporated in vacuo, and the whole extracted 4 times with ether. The ether extracts were combined, washed with saturated sodium chloride solution and dried over anhydrous sodium sulfate. The ester (18 g.) was distilled through a semi-micro distillation apparatus which included a foam-trap and Claisen-head. The material distilling at 53°-4/1.5 mm Hg weighted 13 g. The forerun and pot-residue also consisted largely of the ester. The IR spectrum (CCl_4) showed bands at 1713 (ester $C=O$, conjugated), 1634 ($C=C$, conjugated), 1390-1370 (isopropyl doublet), 1280, 1221 and 1152 cm^{-1} . The NMR spectrum (CCl_4) showed two 6-H doublets (0.96 ppm, $J = 6.4$ Hz, and 1.17 ppm, $J = 7.0$ Hz) for the two isopropyl groups, a 2-H pair of overlapped doublets centered at 2.08 ppm ($J = ca. 6-7$ Hz) for the C-4 methylene group, the O-methyl singlet at 3.67 ppm, and the vinyl triplet (1-H) (6.5 ppm, $J = 7.5$ Hz). The mass spectrum gave peaks at m/e 184 (molecular ion), 169, 153, 142, 141, 137, 128, 127, 110, 109, 95, 83, 81, 75, 69, 67, 59, 56, 55, 53, 43 (base peak) and 41.

EXAMPLE VII

Aliquots of 10 μ l of a solution of 0.5 mg of 2-isopropyl-5-methyl-2-hexenal in 1 ml 95 percent ethanol were injected uniformly along a path of 55 mm length in experimental cigarettes manufactured from a commercial blend of tobaccos. The sample cigarettes were equilibrated at 60 percent relative humidity for 10-12 hrs. before smoking.

The smoke characteristics of samples of the cigarettes were evaluated by an experienced taste panel. Each sample of cigarettes was compared to a corresponding control handled in the same manner as the test sample, but not containing the active flavor ingredient.

Cigarettes containing 2-isopropyl-5-methyl-2-hexenal produced on smoking a low to moderate suggestion of a Turkish tobacco-type flavor and a salty-metallic sour taste complex related to some Turkish types.

EXAMPLE VIII

A solution of 10 mg of 2-isopropyl-5-methyl-2-hexenal in 4 ml of 95 percent ethanol was applied by spraying to 200 gm of a cased and cut commercial blend of tobaccos, and the treated tobacco was made into cigarettes (Sample A). In a similar manner, cigarettes were made employing solutions of 20, 30 and 50 mg of 2-isopropyl-5-methyl-2-hexenal in 4 ml of 95 percent ethanol (Samples B, C and D, respectively).

The cigarettes of Sample A and B exhibited a complex and interesting aroma which had notes of sour, dried fruit, honey and licorice. The smoke from these cigarettes produced a dominant bitter-woody taste and, especially those of Sample B, produced some throat irritation. The cigarettes of Samples C and D exhibited unpleasant astringency and irritation on smoking.

EXAMPLE IX

A solution of 25 mg of 2-isopropyl-5-methyl-2-hexenal in 4 ml of 95 percent ethanol was applied by spraying to 200 gm of a cased and cut commercial blend of tobaccos. The thus treated tobacco was made into 25 cigarettes and cellulose acetate filters were attached. A second sample was prepared in a similar manner, except that three-piece filters consisting of cellulose acetate-charcoal-cellulose acetate were attached instead of the cellulose acetate filter. Cigarettes having attached cellulose acetate filters showed slightly enhanced tobacco fragrance and more fullness, whereas cigarettes having attached three-piece cellulose acetate and charcoal filters gave no improvement over the control on smoking.

EXAMPLE X

A solution of 20 mg of 2-isopropyl-5-methyl-3-hydroxyhexanoic acid in 4 ml of 95 percent ethanol was applied by spraying to 200 gm of a cased and cut commercial blend of tobaccos, and the thus-treated tobacco was made into cigarettes. The cigarettes produced more amplitude, more blended tobacco fragrance, and more sweet taste than the control when smoked. In addition a slight pepperiness was observed.

EXAMPLE XI

A solution of 10 mg methyl 2-isopropyl-5-methyl-3-hydroxyhexanoate in 4 ml of 95 percent ethanol was applied by spraying to 200 gm of a cased and cut commercial blend of tobaccos. The thus-treated tobacco was made into cigarettes (Sample A). In a similar manner samples were produced employing solutions of 20, 30 and 50 mg. of methyl 2-isopropyl-5-methyl-3-hydroxyhexanoate in 4 ml of 95 percent ethanol (Samples B, C and D, respectively).

The cigarettes of Sample A were not significantly different from the control, but those of Samples B produced a more balanced flavor spectrum than the control when smoked, with a higher level of sweet taste, less bitter taste, less drying and a low-level woody character. The cigarettes also produced a smoother, smoke, and a modest taste improvement over the control. The cigarettes of Sample C and D produced a bitter, pipe-stem taste and a high level of pepperiness and sting.

EXAMPLE XII

A solution of 20 mg of 2-isopropyl-5-methyl-2-hexenoic acid in 4 ml of 95 percent ethanol was applied by spraying to 200 gm of a cased and cut commercial blend of tobaccos, and the thus-treated tobacco was made into cigarettes.

Cigarettes prepared in this manner exhibited increased fullness and interest in the smoke, but there were no flavor or taste differences from the untreated control.

EXAMPLE XIII

Aliquots of 10 μ l of a solution of 20 mg of methyl 2-isopropyl-5-methyl-2-hexenoate in 1 ml of 95 percent ethanol were injected uniformly along a path of 55 mm length in experimental cigarettes manufactured from a commercial blend of tobaccos. The sample cigarettes were equilibrated at 60 percent relative humidity for 24 hours before smoking.

These cigarettes produced a smoke which possessed increased amplitude and tobacco fragrance giving better balance and fuller mouth effect than the control.

EXAMPLE XIV

A solution of 10 mg of 2-isopropyl-5-methyl-2-hexenal and 20 mg of methyl 2-isopropyl-5-methyl-3-hydroxyhexanoate in 4 ml of 95 percent ethanol was sprayed onto 200 gm of a cased and cut commercial blend of tobaccos and the blend was made into cigarettes. The cigarettes exhibited enhanced tobacco fragrance which was described as having cocoa-burley character. There was also a more complex flavor spectrum characterized by a woody-Turkish note.

EXAMPLE XV

2-Isopropyl-5-methyl-2-hexen-1-ol was prepared by reduction of the corresponding aldehyde with sodium borohydride in ethanol. After appropriate work-up, the product was obtained by distillation at 61°-62°C/1-2 mm.

Aliquots of 10 μ l of a solution of 20 mg 2-isopropyl-5-methyl-2-hexen-1-ol in 2 ml of 95 percent ethanol were injected uniformly along a path of 55 mm length in experimental cigarettes manufactured from a commercial blend of tobaccos. The solvent was removed from each cigarette by a gentle stream of air.

Upon organoleptic evaluation the cigarettes containing the 2-isopropyl-5-methyl-2-hexen-1-ol exhibited moderate burnt, green, and sweet notes, while drying and coating were low to moderate as were mouth and throat irritations. Bright tobacco-like notes in the after-taste were intensified.

EXAMPLE XVI

Hydrogenation of 2 g. 2-isopropyl-5-methyl-2-hexenal over 0.1 g. platinum oxide and 0.005 g. ferrous chloride in 15 ml. methanol at room temperature and 30-40 pounds pressure produced 2-isopropyl-5-methylhexanol. The product was purified by molecular distillation at a block temperature of 90° and a pressure of 25-30 mm; $\lambda_{\text{max}}^{\text{CCl}_4}$ 2.75, 2.86, (OH); 7.21, 7.31 (isopropyl); 9.57 μ (C=O). The mass spectrum shows a very weak molecular ion and the NMR spectrum is consistent with the assigned structure.

Aliquots of 10 μ l of solution of 2-isopropyl-5-methylhexanol were injected uniformly along a path of 55 mm length in experimental cigarettes manufactured from a commercial blend of tobaccos. The cigarettes were submitted to a flavor panel for organoleptic evaluation. It was found that 25 ppm, a very desirable wetting effect of low intensity is imparted to the smoke of the treated cigarettes along with a slight increase in sour character. At levels of 50 to 200 ppm, the compound contributes undesirable increases in pepperiness, oiliness, green and sour character.

EXAMPLE XVII

2-Isopropyl-5-methylhexyl acetate was synthesized by hydrogenation of lavandulyl acetate in methanol over 5 percent palladium on carbon at room temp. and 30-40 pounds pressure. The product was purified by distillation at 111°-115°/25-30 mm; $\lambda_{\text{max}}^{\text{CCl}_4}$ 5.75 (C=O); 7.19, 7.29 (isopropyl); 8.1 μ (C=O); mass spectrum : M^+ at m/e 200.

Aliquots of 10 μ l of solutions of 2-isopropyl-5-methylhexyl acetate were injected uniformly along a path of 55 mm length in experimental cigarettes manufactured from a commercial blend of tobaccos. The cigarettes were submitted to a flavor panel for organoleptic evaluation. A highly desirable salivating effect is produced at 25 ppm. It was found that at higher levels, a citrus-like character is imparted to the smoke flavor along with burn and peppery notes.

EXAMPLE XVIII

A mixture of 1 g. 2-isopropyl-5-methyl-2-hexen-1-ol, 0.5 g. anhydrous sodium acetate, and 8 ml. acetic anhydride was heated with stirring on a steam bath for 3 hrs. Workup of the reaction mixture by conventional methods followed by molecular distillation at 90°-100°/25-30 mm gave 2-isopropyl-5-methyl-2-hexenyl acetate; $\lambda_{\text{max}}^{\text{CCl}_4}$ 5.75 (C=O), 8.24 μ (C=O); mass spectrum : molecular ion at m/e 198, 138 (M-CH₃COOH). This product can be hydrogenated in known manner to yield 2-isopropyl-5-methylhexyl acetate.

EXAMPLE XIX

2-Isopropyl-5-methyl-2-hexen-1-ol was converted to the corresponding methyl ether by treatment with sodium followed by methyl iodide in anhydrous ether; $\lambda_{\text{max}}^{\text{CCl}_4}$ 5.90 (C=C); 7.21, 7.30 (isopropyl); 9.08 μ (C=O); mass spectrum : molecular ion at m/e 170. The NMR spectrum was consistent with the assigned structure. This product can be hydrogenated in known manner to yield 2-isopropyl-5-methylhexyl methyl ether.

EXAMPLE XX

3-Isopropyl-6-methyl-2-heptanol was prepared from 2-isopropyl-5-methylhexanal by treating 5 g. of the aldehyde with 24 ml. of 1.66 M methyl lithium in 25 ml. anhydrous ether at 10°-15°C under an atmosphere of nitrogen. After addition of the methyl lithium was complete, the solution was stirred under reflux for 1 hour, cooled to 0°C, and hydrolyzed with 15 ml. of ice-cold 15 percent sulfuric acid. The layers were separated and the organic layer was washed with saturated sodium bicarbonate solution, water, and sat-

rated sodium chloride solution, dried over anhydrous sodium sulfate, and the solvent removed on the rotary evaporator. The product was purified by molecular distillation at 100°C/20–25 MM; $\lambda_{max}^{CCl_4}$ 2.75 (OH); 7.20 and 7.30 (isopropyl); 9.17 μ (C—O); mass spectrum: molecular ion at m/e 172.

Aliquots of 10 μ l. of a solution of 10 mg. 3-isopropyl-6-methyl-2heptanol in 1 ml. of 95 percent ethanol were injected uniformly along a path of 55 mm. length in experimental cigarettes manufactured from a commercial blend of tobaccos. The solvent was removed from each cigarette by a gentle stream of air. Upon organoleptic evaluation, the treated cigarettes were judged to produce a smoke characteristic of burley tobacco with subdued robustness and sweet character.

EXAMPLE XXI

3-Isopropyl-6-methyl-2-heptanone was prepared by reacting 2-isopropyl-5-methylhexanoic acid with ethyl lithium as follows: A solution of 2 g. of the acid in 25 ml. anhydrous ether was treated with 16 ml. of 3.5 M methyl lithium in ethyl ether at 10°C under a nitrogen atmosphere. The reaction solution was then refluxed with stirring for 2 hours, cooled to 0°C, and hydrolyzed with 10 ml. of 15 percent sulfuric acid. The layers were separated and the organic layer was washed sequentially with saturated sodium bicarbonate solution, water, and saturated sodium chloride solution, dried over sodium sulfate, and evaporated on the rotary evaporator. The product was purified by molecular distillation at 70°-80°C/20-25 mm; $\lambda_{max}^{CCl_4}$ 5.85 (C=O); 7.21 and 7.30 μ (isopropyl); mass spectrum: molecular ion at m/e 170. 20 30

Aliquots of 10 μ l of a solution of 10 mg. 3-isopropyl-6-methyl-2-heptanone in 1 ml. 95 percent ethanol were injected uniformly along a path of 55 mm. length in experimental cigarettes manufactured from a commercial blend of tobaccos. The solvent was removed from each cigarette by a gentle stream of air. The treated cigarettes were evaluated organoleptically and were judged to produce a smoke having a sharp green note with a slight increase in sour character.

The additives of this invention may be applied to the tobacco by spraying, dipping or otherwise, utilizing

suitable suspensions or solutions of the additive

In addition to being useful in the manufacture of cigarette tobacco, the additives are also suitable for use in connection with the manufacture of pipe tobacco or other tobacco products.

It will be appreciated that while several embodiments of this invention are shown above, the invention is not to be limited thereto, since many modifications will be obvious to those skilled in the art and that the present invention is defined by the appended claims.

What is claimed is:

1. A tobacco composition including in an amount sufficient to modify the organoleptic characteristics of the tobacco at least one compound of the formula:

20 wherein Y is hydrogen, hydroxyl, lower alkoxy or lower acyloxy; X is hydroxymethyl, lower alkoxymethyl, lower acyloxymethyl, 2-hydroxyethyl, formyl, acetyl, carboxyl or lower alkoxy carbonyl; and y is 0 or 1, with
25 the proviso that X is acyloxymethyl or alkoxymethyl only when y is 1.

2. A composition according to claim 1 wherein y is 1 and Y is hydroxyl.

3. A composition according to claim 2 wherein X is a radical selected from the group consisting of hydroxymethyl, formyl, carboxyl and methoxycarbonyl.

4. A composition according to claim 1 wherein γ is 0.

5. A composition according to claim 4 wherein X is a radical selected from the group consisting of hydrox-

35 ymethyl, formyl, carboxyl and methoxycarbonyl.

6. A composition according to claim 1 wherein y is 1 and Y is hydrogen.

7. A composition according to claim 6 wherein X is a radical selected from the group consisting of hydroxyl, carboxyl, and alkoxyl.

40 ymethyl, methoxymethyl, acetoxyethyl, formyl, carboxyl, 2-hydroxyethyl and acetyl.

3. A tobacco smoking article including a tobacco composition according to claim 1.

UNITED STATES PATENT OFFICE
CERTIFICATE OF CORRECTION

Patent No. 3,704,714 Dated December 5, 1972
(Serial No. 153,900) (Filed June 16, 1971)
Inventor(s) Andrew G. Kallianos et al

It is certified that error appears in the above-identified patent and that said Letters Patent are hereby corrected as shown below:

Column 4, line 31, before "(OH-rearrangement)" delete minus sign and insert --116--.

Column 4, line 33, in the Analysis, correct formula to read as follows: -- C₁₁H₂₂O₃ --.

Column 7, line 23, correct spelling of --than--.

Column 10, line 9, correct spelling of --that--.

Signed and sealed this 1st day of May 1973.

(SEAL)
